UNITED STATES PATENT OFFICE

2,262,629

BASE FOR ELECTRIC LAMP OR SIMILAR DEVICE

Daniel K. Wright, Cleveland Heights, Ohio, assignor to General Electric Company, a corporation of New York

Application February 14, 1940, Serial No. 318,885

4 Claims. (Cl. 176—32)

My invention relates to electric incandescent lamps and similar devices comprising a bulb having an electrical energy translation element sealed therein and a base mounted on said bulb. More particularly, my invention relates to the terminal structure for such devices, including the base and the seal structure for the current leads to the filament or other light source. This application is a continuation-in-part of my application Serial No. 250,765, filed January 13, 1939.

One of the objects of my invention is to provide a lamp or similar device in which the usual re-entrant stem tube carrying the lead-in wires is eliminated and the seal or terminal portion of the device is so constructed as to permit the use in combination therewith of a base which may be inserted in ordinary sockets.

For certain definite reasons it is desirable to employ, for high-intensity lamps, a mechanical base in which a firm connection between the lamp bulb and the base is maintained at all times, although in cases where the base portion of the lamp is not excessively heated the said base may be united to the bulb with cement. It is therefore another object of my invention to provide a novel mechanical base structure which is particularly useful for high-intensity lamps.

While mechanical bases have heretofore been proposed in which the base snugly fits the bulb neck and is formed with projections extending into depressions in the bulb neck, such prior constructions are impractical and have proven unsatisfactory. The reason for this is that the bases were applied to conventional blown glass bulbs having relatively thin walls. These thin glass walls cannot readily withstand the pressure exerted thereon by the base deforming tool during the spinning of the base metal into the bulb neck depressions, with the result that they frequently cracked. Nor can such thin glass walls withstand the tremendous pressures exerted thereon by the base during the heating up and cooling down of the lamp, and resulting from the difference in the rates of expansion and contraction of the bulb glass and the surrounding base metal. Consequently, a slight clearance has to be provided between the base shell and the bulb neck to reduce these pressures to a minimum so as to effectively prevent cracking of the bulb glass. But in doing so, a loose and wabbly base is very likely to result.

To provide a practical mechanical base con-

struction which will not result in fracture of the bulb glass and which will not become loose or wabbly on the bulb neck, I have found it necessary to employ a bulb neck of pressed glass having relatively thick walls, and to secure the base on the bulb neck by a relatively tight press fit. Such thick glass walls will readily withstand, without cracking, the pressures exerted thereon during the spinning of the base metal into the depressions in such walls, as well as the pressures exerted by the base during the heating up and cooling down of the lamp. Furthermore, the relatively tight press fit between the base and the bulb neck insures a firmly mounted base at all times, and positively prevents any possibility of the base becoming loose or wabbly on the bulb neck.

Further features and advantages of my invention will appear from the following description 20 of a species thereof and from the accompanying drawing, in which Fig. 1 is an elevation, partly in section, of an electric incandescent lamp provided with a seal structure and a mechanical base comprising my invention; Fig. 2 is a fragmentary view taken at right angles to Fig. 1, with a portion of the base broken away; Fig. 3 is a view, similar to Fig. 2, showing the base in position on the bulb neck preparatory to its application thereto, and Fig. 4 is an elevation, partly in section, of the base and seal portion of a modification employing a cemented base.

Referring to Fig. 1, the lamp there shown is of the reflector type similar to that disclosed and claimed in my United States Patent 35 2,148,314. The lamp comprises a bulb or envelope 10 consisting of a preformed reflector section 11 made of pressed glass and a cover glass section 12 also made of pressed glass. These two 40 sections 11, 12 are sealed together at their peripheries by fusion to thereby form the bulb 10. The interior surface 13 of the reflector section 11 may be of any suitable shape, preferably that of a so-called contracted parabola, and is covered 45 with a metallic coating 14 constituting a reflecting surface. The reflector section 11 is formed at its vertex with a relatively heavy annular neck or shoulder portion 15 having a flat end wall 16. As shown in Figs. 2 and 3, the outer surface 17 50 of the neck 15 is formed with a reduced diameter portion 18 to thereby provide an annular abutment shoulder 19. The reduced diameter portion 18 is formed with a slight taper and is provided with a pair of diametrically opposite indentations or depressions 20 adjacent the shoulder 19.

These indentations are preferably spherical or dish-shaped, and are relatively shallow. A filament 21 is mounted within the bulb 10, in the desired location therein, by means of flexible leading-in wires 22, 23 hermetically united, preferably by brazing, to metal cups 24, 24 having their edges or rims fused to and sunk and embedded in the thickness of the glass end wall 16. The said cups or skirts 24 may be made of an iron-nickel-cobalt alloy known as Fernico.

Secured to the neck 15 of the bulb 10 is a base 25 comprising a threaded metallic shell 26, insulation 27, and a metallic center-contact eyelet 28. Leading-in wire 22 is connected to the shell 26 while leading-in wire 23 is connected to the eyelet 28. The base is provided with an annular metallic skirt 29 having an inwardly extending flange 30 embedded in the insulation 27.

In the mechanical form of base shown in Figs. 1-3, the skirt 29 is mounted on the tapered neck portion 18 of the bulb by a press fit, as shown particularly in Fig. 2, with the rim 31 of the skirt engaging the abutment shoulder 19 on the bulb. To provide a positive interlock between the base and bulb neck, the skirt 29, after its application to the bulb neck, is formed with a pair of inwardly extending projections or lobes 32 extending into and firmly engaging the surfaces of the indentations 20 in the bulb neck.

To form the press fit between the base and the bulb, the skirt 29 is made with an inner diameter intermediate the diameter of the outer and inner ends of the tapered neck portion 18 so that when the skirt is initially placed over the tapered neck, it will fit the same in the manner indicated in Fig. 3. The skirt is then forced down onto the tapered heavy neck portion 18 until the rim 31 of the skirt abuts against the annular abutment shoulder 19 on the bulb, as shown in Fig. 2. The resulting press fit, together with the engagement of the rim 31 with the abutment shoulder 19, combine to positively eliminate all looseness of the base on the bulb so that there is no possibility of the base becoming wobbly or free to rock. Where the skirt 29 is made of relatively thick metal, or the inner diameter of the skirt is of such small dimensions that the pressure exerted on the bulb neck 18 is apt to be excessive, it may be necessary to longitudinally slit the skirt, at two or more spaced points around its periphery, for a short distance from its rim 31. In this manner the excessive pressure which would otherwise be exerted by the skirt 29 on the bulb neck 18 and which might result in cracking of the same, may be reduced to a comparatively safe value while still maintaining a sufficient press fit between the said skirt and bulb neck to perform the functions specified hereinbefore.

After the base has been pressed onto the bulb neck, the metal of the skirt 29 opposite the spherical indentations 20 in the bulb neck is then deformed or depressed inwardly into the said indentations by forcing the same with a suitable tool or by spinning so that the entire inner surface of the resulting projections 32 are disposed in firm contact with the surfaces of the indentations 20.

The press fit between the base and bulb neck provides a rigid mounting for the base whereby it is secured on the bulb in the absence of all play, so that it is only necessary to provide suitable holding means for preventing re-

moval of the base from the bulb or relative rotational displacement therebetween. The projections 32 on the base extending into the indentations 20 on the bulb neck therefore merely serve to lock the base in place on the bulb neck, keeping it against the abutment shoulder 19 on the bulb and preventing relative rotational displacement.

In the modification shown in Fig. 4, the skirt portion 29 of the base 25 abuts against the annular shoulder 19 which serves to center the base on the bulb neck. The said bulb neck is reduced in diameter at 33 to provide space for an annular ring of cement 34 which unites the said base to the bulb neck.

While I have shown and described a preferred embodiment of the invention, it is obvious that various modifications are possible within the scope of the invention. Thus, in the case of the mechanical base structure of Figs. 1-3, while I prefer to employ only two interlocking projections 32 and indentations 20 on the base and bulb neck respectively, any desired number may be employed. Furthermore, instead of employing spherical projections 32 and indentations 20, they may be made of any suitable shape or form to answer the purpose. If desired, the base shell 26 and skirt 29 may be made in one piece, instead of as two separate members as shown.

What I claim as new and desire to secure by Letters Patent of the United States is:

1. The method of attaching a base comprising a metal shell to a bulb, which consists of forming a relatively heavy pressed glass frusto-conical neck portion on said bulb with a plurality of indentations therein, forcing said shell onto said heavy neck portion so as to form a tight press fit therewith, and deforming the metal of said shell opposite said indentations so as to enter and firmly engage the surfaces of said indentations.

2. An electrical device comprising a bulb having a relatively heavy pressed glass neck portion, and a base comprising a metal shell portion shaped to engage with a socket and a separate metal skirt portion surrounding said bulb neck portion and secured thereon by a press fit, said neck portion being provided with at least one indentation therein and said base being formed with a co-operating protuberance in said skirt fitting firmly within said indentation.

3. An electrical device comprising a bulb having a relatively heavy glass neck portion and end wall, said end wall having openings therethrough, an electric energy translation element in said bulb, flexible lead wires extending from said translation element exteriorly of said bulb through the said openings in said end wall, cup-like metallic members having their edges fused to said end wall around the said openings therein to hermetically seal said openings, said lead wires extending through said cup-like members and being hermetically sealed thereto, and a base carrying contacts and comprising a shell portion surrounding said bulb neck portion and fixedly secured thereto, said lead wires being electrically connected to said base contacts.

4. An electrical device comprising a bulb having a relatively heavy pressed glass neck portion and end wall, said end wall having openings therethrough, an electric energy translation element in said bulb, flexible lead wires extending from said translation element exteriorly of said bulb through the said openings in said end wall, cup-like metallic members having their edges

fused to said end wall around the said openings therein to hermetically seal said openings, said lead wires extending through said cup-like members and being hermetically sealed thereto, and a base carrying contacts and comprising a shell portion surrounding said bulb neck portion and secured thereon by a press fit, said bulb neck

portion being provided with at least one indentation therein and said base shell portion being formed with a co-operating projection extending into and firmly engaging the surface of said indentation, said lead wires being electrically connected to said base contacts.

DANIEL K. WRIGHT.
